UNITED STATES PATENT OFFICE.

JOHN PURSELL, SR., OF NEW HAVEN, CONNECTICUT.

HAMMOCK-CHAIR.

SPECIFICATION forming part of Letters Patent No. 257,759, dated May 9, 1882.

Application filed January 14, 1882. (No model.)

To all whom it may concern:

Be it known that I, JOHN PURSELL, Sr., a citizen of the United States, residing at New Haven, in the county of New Haven and State 5 of Connecticut, have invented new and useful Improvements in Hammock-Chairs, of which the following is a specification.

I have produced an adjustable hammock, bed, and chair specially designed for invalids, and 10 adapted for attachment to and use with a bedstead, or with rockers, or with a caster-platform. It is likewise adapted for use as a rocking hammock and as a cradle-bed, and its capacity for these uses renders it a very desirable 15 article of household furniture. The hammock is carried by a single frame, and is rendered taut or made to sag by setting the upper end of the hammock higher or lower in said frame, while the hammock-frame is rendered 20 adjustable in relation to its support. This frame is curved to form the back and the front legs when forming a chair, having inside 25 rack-plates for securing and allowing of the adjustment of the head-round of the hammock, and outside rack-plates within which the rear 30 legs are set to support the hammock-frame in position as a chair. The front and rear legs are pivoted and the rear legs run in the outer rack-plates to allow the hammock-frame to be

Referring to the drawings, Figure 1 represents the hammock-frame adjusted as a chair and hammock; Fig. 2, a vertical section of the same. Fig. 3 represents the hammock-frame 35 adjusted as a bed and as a hammock. Fig. 4 shows the hammock-frame adjusted as a child's cradle-bed, and Fig. 5 a vertical section of the same, and Fig. 6 a detail of the hammock-rack.

The drawings represent the adjustable hammock-frame attachment as applied to rockers; 40 but it is obvious that such attachment may be applied to a bedstead or to a non-rocking support.

The hammock *a* is of a length and width 45 suitable for a hammock or bed, and is mounted in a carrying-frame composed of side bars, *b b*, suitably braced and connected by cross-bars *cc'* at points so as not to interfere with the mounting and hanging of the hammock. The side 50 bars are preferably of the form of a cyma re-

versa, and are pivoted at their lower ends to their supports, which may be the front ends of the rockers *A*, as shown. The sacking bottom or hammock is mounted upon end rounds, *d d'*, the lower round, *d*, of which is fixed to 55 and between the front legs of said bars *b b*, above or outside of a plane across the upper curved edges of said front legs, *b'*, so as to form the hammock-seat. The upper or head round, *d'*, is adjustable up and down in slotted 60 rack-plates *e*, secured to the inner sides of the upper ends of the said curved frame-bars. The upper hammock-round is set up or down to give the hammock a position for use as a chair or hammock, as shown in Figs. 1 and 2, and 65 as a child's bed, as shown in Figs. 4 and 5, and to give it tautness for use as a bed and hammock, as shown in Fig. 3. The slotted rack-plates are adapted to receive headed bearings *f* of the head-round and allow the heads of the 70 bearings to move freely within or behind the plates in setting the round up or down, but prevent the possibility of the accidental slipping out of the head-round.

The upper curved end of the carrying-frame 75 is connected with and supported by the rear legs, *g*, pivoted at their lower ends to their supports, which may be the rockers, as shown, the upper ends of said legs *g* being adjustably connected to the said carrying-frame rack-plates. 80 This adjustable connection is formed by slotted rack-plates *h*, secured to the outer sides of the frame-bars *b b* and projecting from the lower edges thereof, so as to receive headed bearing-pins *i*, projecting outward from the said supporting-legs *g* and into and through the slots of the racks. These slotted rack-plates are of 85 a length to allow the rear legs, *g*, to sustain the hammock-frame in the desired elevated position for a chair or for a hammock, and to allow 90 the said arms and hammock-frame to be folded in horizontal positions upon the supports or rockers for a bed, for a hammock, or for a child's cradle-bed. In this position the rounds *c'* of the pivoted rear legs, *g*, rest upon the 95 upper edges of the rockers, and the under curved edges of the hammock-carrying frame are supported upon the folded legs, the ends of which stand above the rockers, to bring the head-round of the hammock or sacking on a 100

level, or thereabout, with the fixed round *d* when the former is in sagged position for a cradle-bed, as shown in Fig. 5.

- The hammock-frame and its adjustable supporting rear legs, when used to form a rocking article, as shown, are pivoted to the outer sides of the rockers, which are connected by rounds in the usual manner. When used as an invalid-chair or elevated hammock the hammock 5 can be adjusted in a taut or sagging position, as may be desired. When used as a child's cradle-bed the hammock head-round is set low down in the rack-plates, so as to sag the bottom between the side bars, *b b*; and when said 10 hammock is set in its extended or taut position it will be above the said side bars, so that it forms both an adjustable and a rocking hammock, chair, and bed. The reverse curved ends of the hammock-frame give the head and 15 seat supports for the hammock-rounds in proper relation to the front legs and to the back of said frame, and give the advantage of mounting and adjusting the hammock within a single frame.
- 20 The round *d* is secured in projections *a' a'* outside of a cross-plane of the upper edges of the front legs, *b' b'*, so as to form the hammock-chair seat, and the front rocker-round, *j*, forms the foot-rest.
- 25 Any suitable foot-rest may be used, attached either to side bars or to the rockers.
- The projections *a' a'* for the seat-round may be formed with the side bars, *b b*, or by bearing pieces secured to said side bars. The side bars, 30 *b b*, are provided with suitable arm-rests, *k k*, as shown.

I claim—

1. In a reclining hammock-chair, the combination, with the pivoted adjustable frame forming the front legs, and the back provided with the inside slotted rack-plates, *e*, of the hammock *a*, secured to a fixed round, *d*, of the front legs, and to an adjustable head-round, *d'*, provided with headed bearings *f*, interlocking with said slotted rack-plates, substantially as described, for the purpose specified. 40
2. The combination, with the pivoted adjustable frame, forming the front legs, and back provided with the outside slotted rack-plates, *h*, and hammock-seat, of the rear pivoted legs, *g*, provided with headed bearings *i*, interlocking with said slotted rack-plates, and means, substantially as described, for connecting the front and rear legs, for the purpose set forth. 45
3. The hammock chair and bed herein described, consisting of the pivoted frame provided with inside and outside slotted rack-plates, *e h*, the hammock *a*, the rear pivoted legs, *g*, and the rockers *A*, the upper round of the hammock and the upper ends of the rear 50 legs having headed bearings interlocking with said slotted rack-plates, substantially as described, for the purpose specified. 55

In testimony whereof I have hereunto set my hand in the presence of two subscribing witnesses.

JOHN PURSELL, SR.
